UNITED STATES PATENT OFFICE.

JOHN MAYES, OF PORT AUSTIN, MICHIGAN, ASSIGNOR TO MAYES BROTHERS TOOL MANUFACTURING COMPANY, OF PORT AUSTIN, MICHIGAN, A CORPORATION OF MICHIGAN.

PLASTERER'S FLOAT.

Application filed February 3, 1928. Serial No. 251,652

My invention relates to plasterers' floats and it is an object of the invention to provide a light weight durable float which will not warp or split and one having retaining walls 5 at its sides for increasing its carrying capacity and adding to its rigidity; also a float having beveled ends with comparatively sharp edges which may be used for cutting whenever needed, which enables sharp corners to 10 be neatly plastered, all as will be hereinafter more fully explained.

Referring to the accompanying drawings which are made a part hereof and on which similar reference characters indicate similar 15 parts,

Figure 1 is a perspective illustrating the application of my invention,

Figure 2, an end elevation, and

Figure 3, a fragmentary detail section on 20 the line 3-3 in Figure 1.

In the drawings reference character 10 indicates a rectangular body preferably formed of aluminum or other light weight metal which has a low coefficient of expansion and 25 is of sufficient thickness to afford the necessary rigidity. The rectangular body 10 is provided with the usual handle 11 which may be of wood or metal and secured in position by any desired fastening means. Side flanges 30 12 extend upwardly at right angles to the body 10 at the edges of said body and serve to hold mortar, cement or the like to keep the same from sliding off, thereby greatly increasing the amount of material that may be 35 carried on the float.

The ends 13 of the float are beveled, each of the beveled ends forming a cutting edge which enables the device to be used more advantageously in plastering sharp corners, 40 angles, and the like. The side walls 12 rein-

force or stiffen the body of the float and are tapered from the sharp ends back for a distance to provide a tool with pointed ends to facilitate its use in corners. On account of this construction the corners do not become 45 rounded by wearing faster than their middle portions, which contributes to the life of the tool.

It will be obvious to those skilled in the art that various changes may be made in my device without departing from the spirit of my invention, and I therefore do not limit myself to what is shown in the drawings and described in the specification but only as indicated by the appended claims.

Having thus fully described my said invention, what I claim as new and desire to secure by Letters Patent is:

1. A device of the class described comprising a flat elongated body formed of relatively thin material having its side edges upturned, said elongated body having its ends beveled to form thin cutting edges, and a handle fastened between said upturned side edges intermediate the ends of the body, substantially 60 as set forth.

2. A plasterer's float comprising an elongated body having a flat under surface and upstanding sides disposed at right angles to the flat bottom surface, said body having its 70 ends beveled to form a thin cutting edge, and a handle fastened over the body of the float between the upstanding side walls, substantially as set forth.

In witness whereof I have hereunto set my 75 hand at Port Austin, Michigan this 18th day of January, A. D. nineteen hundred and twenty-eight.

JOHN MAYES.
